(57) **CLAIM**

The ornamental design for a monitor television receiver with an earphone, as shown and described.

DESCRIPTION

FIG. 1 is a perspective view of a monitor television receiver with an earphone showing my design;
FIG. 2 is a top plan view thereof;
FIG. 3 is a bottom plan view thereof;
FIG. 4 is a left side elevational view thereof;
FIG. 5 is a right side elevational view thereof;
FIG. 6 is a front elevational view thereof; and
FIG. 7 is a rear elevational view thereof.

FIG. 8 is a reference rear view thereof, wherein the frame is in folded condition; and,

FIG. 9 is a reference perspective view thereof, wherein the earphones are in pulled condition.

FIGS. 8 and 9 are for illustrative purpose only and form no part of claimed design.
